CLAIM

(22) Filed: **Nov. 15, 2019**

The ornamental design for rear end portion of motor vehicle, toy and/or replica, as shown and described.

(30) **Foreign Application Priority Data**

DESCRIPTION

May 17, 2019 (DE) 402019100569.2

FIG. 1 is a front perspective view of a rear end portion of motor vehicle, toy and/or replica showing my new design; FIG. 2 is a rear elevation view thereof; FIG. 3 is an elevation view from the left side thereof, the right side being a substantial mirror image thereof; and, FIG. 4 is top plan view thereof.

(51) **LOC (13) Cl.** **12-16**

The rear end portion of motor vehicle, toy and/or replica shown in broken lines are for illustrative and environmental purposes and form no part of the claimed design.
